Attorney

UNITED STATES PATENT OFFICE.

STEPHEN HARDER, OF WASHINGTON, DISTRICT OF COLUMBIA.

LINE-JUSTIFICATION-INDICATING MECHANISM.

Application filed November 7, 1922. Serial No. 599,612.

To all whom it may concern:

Be it known that I, STEPHEN HARDER, a citizen of the United States, residing at Washington, in the District of Columbia, have invented certain new and useful Improvements in Line-Justification-Indicating Mechanism, of which the following is a specification.

This invention relates to machines for preparing or composing controllers or record strips for automatic type casting and similar machines, and has particular reference to improvements in the line justification indicating mechanism.

The improvement is particularly adapted for use with the justification space indicating mechanism shown in Patent No. 1,283,623, which patent shows certain improvements upon such mechanism, shown in Patent No. 944,405.

In Patent No. 1,283,623, a lever is automatically swung upon its pivot, and operates a valve, and this valve will then discontinue the operation of the justification indicating mechanism. This lever is swung upon its pivot when the upwardly moving bar, which carries the pointer cooperating with the justification chart, has reached a predetermined position. The bar reaches this position after a predetermined number of justification spaces are placed in a line, and should the operator again touch the justification space key, the further movement of the bar will swing the lever and shift the valve, as above stated.

Should the operator, before the predetermined number of justification spaces has been reached, desire to prevent further justification spaces from being recorded in the line, he moves a rod forwardly or toward him, and the movement of this rod raises a bar which swings the lever upon its pivot, to shift the valve, in a similar manner as occurs when the justification rack has reached the upper predetermined position. This construction is well known and possesses marked advantages.

However, it frequently happens, during the setting of one line, that the operator will move the rod forwardly, to prevent further

justification spaces from being recorded in the line, and when the end of the line is reached, he will forget to shift the rod rearwardly to the normal position, so that the justification space indicating mechanism will be restored to the operative condition. As a result of this, the justification space indicating mechanism will not properly function in setting the succeeding line.

In accordance with my invention, I propose to provide a device which will automatically move under or engage with the valve shifting lever, or the extension thereof, when the lever is swung upon its pivot, as the rod is moved forwardly. The rod may now be returned to the inner or rear position as soon as it has been moved forwardly for elevating the bar which swings the lever. By this means, there will be no tendency for the operator to forget to return the rod, with the results which flow from such neglect. When the complete line has been set, and the several parts of the machine reset, as by the pressing of the resetting key, the pawl or pawls which engage the teeth of the justification rack are thrown out of engagement with such rack, to permit of the same being reset, and these pawls are employed to operate the element engaging with or beneath the lever to operate the valve, whereby such element releases the lever which will return to its normal position, allowing the valve to be restored to its normal condition, and hence the justification space indicating mechanism will be properly restored. In other words, as soon as the line is set, the justification space indicating mechanism will be restored, just as if the rod had remained in the forward position, and was forced rearwardly to the normal position, at the end of the line, as is now the practice.

In the accompanying drawings forming a part of this specification, and in which like numerals are employed to designate like parts throughout the same.

Figure 1 is a perspective view of justification space indicating mechanism, having my device applied thereto,

Figure 2 is a side elevation of my device

or attachment, showing the holding element in the released position, and,

Figure 3 is an edge elevation of the device, with associated elements in elevation.

5 The same reference characters employed in Figures 3 and 4 of Patent No. 1,283,623, will be used, in describing the parts which are old and shown in this patent. 85 is the space counting bar, operating in a guide 85'. 10 86 and 87 are the lifting and holding pawls, acting on the teeth *a* of the bar 85 and controlled by the motor 90. 198 is a valve, controlling through the shift valve, the transference of the signal from the punches for 15 the justifying space to those of the non-justifying space. 201^a is the valve operating lever acting upon the valve 198.

Upon the inner end of the lever 201^a is pivoted at 14 a three arm lever, one arm 13 20 of which forms a finger piece or the like, while the arm 15 is adapted to rest on the lever 201^a and the arm 16 projects into position to cooperate with the shoulder 17 on the space bar 85 and to be acted on by the 25 upper end of the manually controlled bar 10. The three arm lever forms a releasable extension of the lever 201^a, forming a proper connection between the lever 201^a and the bar 85, and allowing of the ready removal 30 of the bar 85, as clearly set forth in Patent No. 1,283,623.

The vertically movable bar 10 is adapted when elevated to engage the arm 16 and through it move the lever 201^a and the valve 35 198. This bar 10 is manually controlled through the medium of a knob or finger piece or rod 11 mounted to slide in bearings in the frame and provided with a cam or inclined face 12 for cooperation with the 40 lower end of the bar 10.

The elements so far described are old and well known and are set forth particularly in Figures 3 and 4 of Patent No. 1,283,623.

Attention is also called to the trip 92, 45 which is shown in Figure 3 of Patent No. 1,283,623 but is not therein numbered. Attention is also called to Patent No. 944,405, above referred to, particularly to Figure 19 thereof. This trip 92 is clearly shown in Figure 19 and is arranged to engage with pins 94, carried by the pawls 86 and 87. As is clearly set forth in Patent No. 944,405, when a line has been completed, the various parts of the machine are reset, by the striking of a resetting key, and this action causes the trip 92 to move toward the pawls 86 and 87, whereby these pawls disengage the teeth *a* and are swung outwardly away from these teeth, so that the bar 85 may descend or be reset. This outward movement of the pawls is ordinarily called "kicking-off" of the pawls.

My device or attachment embodies an inverted L-shaped support or plate B, which

is rigidly secured to the guide 85' by screws 65 C. The plate B has pivotal connection at D with a holding element E. This holding element projects upwardly beyond the pivot in the form of an extension F, having connection with a spring G secured to an extension H of the plate B. The lower end of the holding element E is provided with a laterally extending finger I, which is adapted to rest in engagement with the side of the arm 16. The element E is also provided with an extension or tail J, disposed generally at a right angle to the finger I. The extension J is located across the pawls 86 and 87, and is so arranged that when these pawls are thrown outwardly to release the rack 85, 70 such pawls will engage the extension J, and swing the holding member E outwardly upon its pivot.

In the operation of the machine, the rack 85 is moved upwardly, as explained in Patents Nos. 1,283,623 and 944,405, whereby the justification space indicating mechanism is operated. This action is caused by the operation of the justification space keys, the air 85 passing to the motor 90 each time a justification space key is actuated by the operator, and also to the motors of the justification space punches. The motor 90 acting on the arm 91 raises the lifting pawl 86, which, engaging the teeth of the justification space 90 mounting bar 85, raises the latter through one division. Should the operator, after the predetermined number of justification 95 spaces that are to be placed in a line is reached, again touch the justification space key, the bar 85 in rising will lift the arm 15 through the engagement of the shoulder 17 and this will cause the lever 201^a to turn on its pivot *d* and operate the valve 198. The valve 198 will operate to allow air to pass to 100 shift the valve 20 so as to close the communication of the space signal keys with the space signal punch motors, and transfer the communication to the punches of an ordinary space. The motor 90 receives its motive fluid through one of the justification 105 punch motors, so that when the power is shut off from this motor by the operation of the valve 20, no further movement of the bar 85 would take place.

With the bar 85 thus elevated, and the outer end of the lever 201^a elevated, the holding element E is automatically shifted toward the lever 201^a, and its finger I will slide under the lever 201^a. The spring G will hold the element E in this position, until the parts are reset, by the pressing of a resetting key, at which time pawls 86 and 87 are swung outwardly and engage the extension J and shift the element E outwardly 110 so that the extension I is withdrawn from beneath the lever 201^a, which is now reset. It is thus seen that under these conditions, 115 120 125

the presence of the holding element E does not interfere with or alter the normal operation of the mechanism.

Should the operator, before the predetermined number of justification spaces has been reached, desire to prevent further justification spaces from being recorded in the line, he moves the rod 11 forwardly in the direction of the arrow, and the operation will take place as clearly described in Patent No. 1,283,623. Instead of allowing the rod 11 to remain in the forward or withdrawn position until the line is completed, the operator at once returns the rod 11 to the inner or rear position as soon as it has been shifted to the outer position, thus eliminating the liability of the operator forgetting that the rod 11 is in the outer position, and allowing it to remain in this position, during the setting of the next line. As soon as the rod 11 is thus shifted to the outer position, the bar 10 arises, and by engaging the arm 16, swings the lever 201^a upon its pivot, as explained. The instant that this lever is swung upon its pivot, the finger I slips under the lever and hence holds or locks it against a return movement. Therefore, when the rod 11 is pushed to the inner or rear position, immediately, as described, the lever 201^a is held in the shifted position, just as if the rod 11 remained in the open or forward position. The lever 201^a is held in this shifted position until the end of the line is reached, at which time a resetting key is struck, and the parts of the machine are reset, including the movement of the trip 92 for throwing the pawls 86 and 87 outwardly. When these pawls move outwardly, to reset the bar 85, then engage the extension J and the element E disengages or releases the lever 201^a, which is free to return to its normal position.

It is to be understood that the form of my invention herewith shown and described is to be taken as a preferred example of the same, and that various changes in the shape, size, and arrangement of parts may be resorted to without departing from the spirit of my invention, or the scope of the subjoined claims.

Having thus described my invention, what I claim is:

1. In line justification indicating mechanism of the character described, the combination with a vertically movable space counting bar, of a valve actuating lever arranged in cooperative relation to the bar and having a part shifted by the bar when the bar moves to a selected position, a holding device arranged near the lever and adapted to automatically move into locking engagement therewith when the lever is shifted from the normal position, and means to advance said bar, said means also serving to operate the holding device for releasing the lever, when

said means are shifted to the inactive position for resetting said bar. 65

2. In line justification indicating mechanism of the character described, the combination with a vertically movable space counting bar having teeth, of pawl means to engage the teeth and advance said bar, a trip to move the pawl means out of engagement with said teeth in resetting said bar, a valve actuating lever arranged near said bar and carrying a part adapted to be shifted by the bar when it is moved to a selected position, a holding device arranged near the lever and adapted to automatically move into locking engagement with said part of the lever when the same is shifted from the normal position, 70 said device having an element correlated with the pawl means whereby the element is engaged and shifted by said pawl means when said pawl means is moved out of engagement with said teeth, and manually operated 75 means serving to engage the part carried by the lever and shift said lever from its normal position. 80

3. In line justification indicating mechanism of the character described, the combination with a vertically movable space counting bar, of a valve actuating lever arranged in cooperative relation to the bar, a connector carried by the lever and arranged to be engaged and moved by a part of said bar, a pivoted holding element having a finger normally resting upon one side of said connector and adapted to move beneath said connector when the connector is shifted upwardly, a spring to move the pivoted holding element in one direction, an extension carried by the holding element, pawl means to advance said bar and also serving to engage and shift said extension, a trip to move the pawl means away from said bar, and manually operated means to engage with said connector and shift it upwardly from the normal position. 90 95 100 105

4. In line justification indicating mechanism of the character described, a movable justification space counting member, means for moving said member in accord with the number of justification spaces designated, a member for interrupting the formation of justification space indications, a connector intermediate said members, said connector being adapted to be engaged and shifted by the justification space counting member, an automatically operating holding element adapted to move to a position beneath said connector when the connector is shifted from the normal position, means actuated by the moving means for shifting the holding element to the releasing position, and manually operated means to shift said connector 110 115 120 125 from the normal position.

5. In line justification indicating mechanism of the character described, a movable

justification space counting member, means for moving said member in accordance with the number of justification spaces designated, a device for interrupting the formation of justification space indications thrown into action when the justification space counting member is shifted to a selected position, an automatically operating holding element adapted to move to a locking posi-

tion with relation to the interrupting device when said interrupting device is shifted from the normal position, said holding element being adapted to be shifted by said moving means to a releasing position, and manually operated means to shift said interrupting device from the normal position. ¹⁰

In testimony whereof I affix my signature. ¹⁵

STEPHEN HARDER.
